Letters Patent

The Schedule referred to in these Letters Patent and making part of the same containing a description in the words of the said Athel Town himself of his improvement in Bridges.

Suppose a vertical plane against the side of which are placed the sides of a number of equal and similar flat pieces of timber or other substances of suitable dimensions in such manner as that they shall be parallel to each other say between two horizontal lines in the plane and incline so as to make an angle with the horizontal lines of about 45° or any angle that may be necessary for a brace (as they do the office of a brace) upon which place another series of timber, or other substances of equal dimensions, distance apart and inclination to the horizontal lines in the same manner and between the same parallel to equal diamonds and half diamonds. Hence the longer the pieces are in proportion to the distances between them the smaller will be the diamonds, the more times each piece in one series will be crossed by those of the other series, consequently the greater number of joints, and therefore the more strength and less strain upon each joint when weight or power is applied. But as all plain figures of more than three sides are susceptible of having their angles and areas varied, as also the relative position of their sides, so the above diamond work if secured at all all by joints or intercalation, would be insufficient to resist power properly applied to it for the purpose of levering or altering its diamond divisions without other timbers or other substances running horizontally vertically or otherwise so as to serve as diagonals to a suitable number of the diamonds and thereby dividing them into triangles, figures which are not susceptible of the change before stated of position, angles and area, supposing then the combination of timbers or other substances to remain in the same position as before stated, but that the supposed vertical plane be removed; suppose also that two timbers or other substances of sufficient tension strength be applied one on each side of the lower ends of the two series of timbers or other substances as to

Drawing made for

lay horizontally and have their centres correspondent to or pass through or over the centres of those lower points; and that also two other timber or other substances capable of bearing a sufficient thrust strain pass like manner along on each side of the upper ends, as joints of the two series of timbers or other substances, and also if necessary other similar horizontal pieces may be placed in like manner on each side of the two intermediate rows of joints next to the two former ones and so on as far as the extent of the contemplated arch or span may require, after which secure all the joints by 1. 2. 3 or more trunnels or iron bolts with wedges to the trunnels, and heads and nuts to the bolts to keep all the parts of a joint in close contact. If this combination be extended to any necessary length and piers or other supports be placed at any reasonable distance from each other and the size and quantity of the substances of which the parts are composed be suitable to this distance between the piers or supports considered in connection with the weight that is necessary the combination should sustain as also the manner the weight will be distributed upon it. Then will this construction become the basis of a Bridge in which it is supposed the least weight of material, least expense, but greatest strength and permanence, will be found. It will be subject to the least and easiest repair and have no lateral pressure against the piers or abutments, but containing its whole strength and power to support weight within itself, and only requiring particular supports for its own weight. Should circumstances or taste require any curve for the intrados of an arch leaving the extrados still a straight line or any other either with its convex side up or in an inverted position or should the extrados be thus raised, and the intrados remain a horizontal line the principle as to arrangement of material and as to connecting the joints will remain the same. It only requiring that the upper and lower ranges of joints or intersections of the two series of braces should fall regularly into the lines or curves of the intrados and extrados and which will form the intermediate rows or ranges of intersections so as regularly to harmonize the intrados or extrados by intermediate stronger or curvaceous passing over the joints on each side and secured by trunnels or bolts to as before in ~~the~~ ~~the~~

the same species. The proposed bridge from this Bridge
consists of a number of main and intermediate piers, in the
number of which, the size of the piers and in the manner of ac-
cording to connecting them, materials at the joints should now be used in the
construction of the trusses, especially that now the construction at the joints
will be formed partly of flanges or otherwise so as to require if any but one
set of supports, and the piers might be somewhat reduced between the joints
without any loss of strength of the trusses.

The pier may be formed of one or more trusses or tresses and the floor placed on
any of the horizontal strong pieces that the circumstances may require, in
which case the truss is to be made the floor may project on each side having
its outer edges suspended to the top strong piece of the truss with a fair braced
top-slope boarding for stamping, but if the floor be too high up in the
truss, its outer edges might be braced wholly or in part from the lower strong
piece and so diminished by resting on the piers to retain its fair fair position
and strength.
